(57) **CLAIM**

The ornamental design for an electronic cooking fork, as shown and described.

DESCRIPTION

FIG. 1 is a perspective top side view of an electronic cooking fork, showing our new design;

FIG. 2 is a top plan view of the electronic cooking fork shown in FIG. 1;

FIG. 3 is a bottom view of the electronic cooking fork shown in FIG. 1;

FIG. 4 is a right side view of the electronic cooking fork shown in FIG. 1;

FIG. 5 is a left side view of the electronic cooking fork shown in FIG. 1;

FIG. 6 is a distal end view of the electronic cooking fork shown in FIG. 1;

FIG. 7 is a proximal end view of the electronic cooking fork shown in FIG. 1; and,

FIG. 8 is a perspective bottom view of the electronic cooking fork shown in FIG. 1.

The broken lines in the drawings form no part of the claimed design for an electronic cooking fork.
